Inventor:

Alessandro Cefitoro

UNITED STATES PATENT OFFICE.

ALESSANDRO CAPITANO, OF PITTSTON, PENNSYLVANIA.

SQUARE.

1,383,073.

Specification of Letters Patent. Patented June 28, 1921.

Application filed June 5, 1920. Serial No. 386,880.

To all whom it may concern:

Be it known that I, ALESSANDRO CAPITANO, a citizen of the United States, residing at Pittston, in the county of Luzerne and State 5 of Pennsylvania, have invented a new and useful Improvement in Squares, of which the following is a specification.

My invention relates to folding or combination squares such as are used by various 10 mechanics and consists in providing improved features in such squares whereby they become capable of being used for many different purposes, and take the place of squares, calipers, bevels, T-squares, protractors, etc., a single compactly foldable device 15 thus serving as a substitute for a large number of separate tools.

One form which my invention may take is described in the present specification and 20 illustrated in the accompanying drawings, wherein:

Figure 1 represents the device adjusted to act as an ordinary square or bevel square.

Fig. 2 is a side view from the left of 25 Fig. 1.

Fig. 3 is a section of one shank of the square on the line 3—3 of Fig. 1.

Fig. 4 represents a locking device shown 30 in Fig. 1 which serves to retain the square in its adjusted position, the parts being shown in section.

Fig. 5 represents one way of holding the sliding blade.

Fig. 6 represents a modified way. 35 Figs. 7 and 8 represent supplemental dials which may be applied to the device.

Fig. 9 shows the device adjusted for use as a T-square.

Figs. 10, 11 and 12 show supplemental 40 blades adapted for use in the device.

My improved square comprises two principal elements, namely the shank 1 and the blade 2. These are pivotally joined at 3 whereby they may be adjusted angularly 45 with respect to each other, to serve as a bevel or square. The shank 1 is slotted at 4 to receive the blade 2, which folds into it when in closed position in the usual manner. The blade 2 is notched at 5 to clear the portion 50 6 of the shank, when closed. While the material of which the device is made forms no part of my invention, it will be understood that metal will usually be preferred. A dial 7 is provided concentric with the pivot 3, 55 preferably cut or stamped directly in the

material of the shank itself. This dial may be graduated in any desired way, for instance, in degrees or pitches, and the particular graduations form no part of my invention. A similar dial 8 shown in Fig. 9 is 60 provided near the center of the shank 1 and is used when the blade 2 is positioned for use as a T-square. A blade 2^a similar to blade 2 may be provided if desired. The blade 2^a differs from blade 2 chiefly in that 65 it has a squared end without the notch 5 of blade 2, and may be made short enough to clear the portion 6 of the shank 1. This is desirable in some cases where the notch 5 would interfere with the work. 70

A pair of sliding blades is also provided, these blades being designated by reference characters 9 and 10, the former sliding in a groove in shank 1, the latter in a similar groove in the blade 2. These sliding blades 75 are slidable in the direction of their length, and may be projected more or less until their pointed ends 11 and 12 meet at the vertex of the angle formed by the outer edges of the shank 1 and blade 2, as shown in Fig. 1. 80 The cross section of the blade 9 is shown in Figs. 5 and 6, blade 10 being exactly the same. The blades are housed in grooves of appropriate shape and are adjustable to a limited extent by means of the screws 14 85 moving in slots 16. In Fig. 5 a screw 14 is shown whose head bears against the edges 15 of slot 16, and whose threads are engaged in the sliding blade 9. Upon loosening this screw 14 slightly, the blade 9 may be adjusted, and then clamped securely by again tightening the screw 14. A modified arrangement is shown in Fig. 6, wherein a screw 18 is engaged through slot 16, and threaded into a nut 17, which bears against 90 the edges 15 of the slot 16. A slot may be provided at each end of the screw 18, so that the adjustment may be made from either side of the instrument. ●

Although the instrument is originally provided with the two dials 7 and 8 marked upon its surface, in time rough usage, or even ordinary wear and corrosion, may obliterate the graduations. I therefore provide supplemental dials 19, 20, shown in 100 Figs. 7 and 8. These dials fit over the original dials 7 and 8, and thus form ready means of repairing the device. They are fastened by nails or screws passed through the holes 21, and have central holes 22 to pass the 105 110

spindle of the indicator hereinafter described.

The dials coöperate with indicator 23, shown in one location in Fig. 1, and in its other location in Fig. 9. It consists of a four-pointed star-shaped flat piece of metal 24 one of the "points" of the star being widened and carrying a clamping means, 25, the other three "points" being sharp, and disposed accurately at 90° from each other on the dial, any one of them serving as a reading pointer. As shown in Fig. 4, the indicator 23 carries the clamping means 25 (a knurled thumb screw as shown) which when tightened will cause a portion of the shank 1 to be tightly clamped between the lower clamp plate 26 and the upper clamp plate 27. The dials are located in circular depressions, whose cross section is shown in Fig. 4. The indicator is secured, as by means of a squared hole coöperating with a squared pintle, to rotate with the blade 2 (or 2^a), one means of doing this being shown in Fig. 3. Here a flange 28 on a short shaft 29 has a square portion 30 on its upper face, to coöperate with a similarly shaped hole 31 in the indicator 23, and a set screw 32 serves to secure it firmly to the indicator. Below the flange 28 the shaft has a round portion 33, and below this another square portion 34, which engages a similarly shaped hole 41 in the blade 2 or 2^a to cause the shaft to revolve with the blade. Passing through part of the shaft 29 is a swivel pin 35 secured at one end to the screw threaded rod 36, and having its other end riveted or otherwise enlarged so as to rotate freely in shaft 29 but to be held from falling out. A nut 37 of the type shown serves to tighten the rod 36 and pin 35 to hold the parts in place.

Undercut grooves 38, 38, are provided across blade 2, and are adapted to engage corresponding bars 39, 39, shown in Fig. 11, of blade 40. The blade 40 may be substituted for blade 2 or 2^a, and then blade 2 may be placed with the grooves 38 in engagement with bars 39, 39. While these may be separate bars, it is preferred in practice to unite them by a thin sheet of metal to strengthen them.

In use, the device when assembled as in Fig. 1 will serve as a square or bevel, the angle the shank 1 and blade 2 make with each other being readable on dial 7. The 55 slidable blades 9 and 10 are adjusted so that their tips 11 and 12 meet at a point, which will be the vertex of the angle the outer edges of shank 1 and blade 2 make with each other. When the shank and blade are assembled as in Fig. 9, the device serves as a T-square whose angle is adjustable and readable on dial 8. When the supplemental blade 40 shown in Figs. 11 and 12 is inserted in place of blade 2, the blade 2 or 2^a may be engaged over the bars 39, 39 which slide in

grooves 38, 38. The shank 1 and blade 2 or 2^a may thus be set to a given taper or a uniform parallel spacing, depending upon the angle at which blade 40 is clamped to the shank 1. When the angle is a right angle, 70 the device may be used as a caliper, the object to be measured being placed between the shank 1 and blade 2 or 2^a, which is then moved along the bars 39, 39 until it engages the object between itself and the shank, the measurement being then indicated by the scales on bars 39, 39.

Having described one embodiment of my device, I claim as my invention:

1. A combination square having a shank 80 and a blade, a pair of dials one near the middle of the shank, the other near one end of the same, an indicator, means for releasably securing the same rigidly to the blade, and arranged to coöperate with one of the 85 dials, means for locking the indicator to the shank and thereby secure the shank and blade in their adjusted positions.

2. A combination square having a shank 90 and a blade, a pair of dials one near the middle of the shank, the other near one end of the same, an indicator, means for releasably securing the same rigidly to the blade, and arranged to coöperate with one of the 95 dials, means for locking the indicator to the shank and thereby secure the shank and blade in their adjusted positions, and an auxiliary blade slidable in one of the members of the square, having a pointed end which remains in line with the outer edge of said 100 member.

3. A combination square having a shank 105 and a blade, a pair of dials one near the middle of the shank, the other near one end of the same, an indicator, means for releasably securing the same rigidly to the blade, and arranged to coöperate with one of the 110 dials, means for locking the indicator to the shank and thereby secure the shank and blade in their adjusted positions, and an auxiliary blade slidable in one of the members of the square, having a pointed end which remains in line with the outer edge of said member, and means for securing said auxiliary blade in its adjusted position. 115

4. A combination square having a shank 120 and a blade, a pair of dials one near the middle of the shank, the other near one end of the same, an indicator, means for releasably securing the same rigidly to the blade, 125 and arranged to coöperate with one of the dials, means for locking the indicator to the shank and thereby secure the shank and blade in their adjusted positions, and a pair of auxiliary blades slidable in the shank and blade respectively, each having a pointed end, which remains in line with the outer edge of the member in which the respective auxiliary blade is seated.

5. In a device of the character described, 130

a shank having a circular depression, and having a dial marked in the material of the shank itself, and an auxiliary dial plate fitting in said depression and secured therein.

5. 6. In a device of the class described, a shank, a member having a bar of trapezoidal cross section extending therefrom, said mem-

ber being pivotally secured to the shank, and a blade having a transverse groove therein, fitting slidably over said bar, whereby 10 the blade may be moved toward or from the shank along said bar.

ALESSANDRO CAPITANO.
